UNITED STATES PATENT OFFICE.

HERMAN G. SCHROEDER, OF LINCOLN, NEBRASKA.

WRITING INSTRUMENT.

1,150,068.

Specification of Letters Patent. Patented Aug. 17, 1915.

Application filed August 15, 1913. Serial No. 784,938.

To all whom it may concern:

Be it known that I, HERMAN G. SCHROEDER, a citizen of the United States, residing in Lincoln, in the county of Lancaster and State of Nebraska, have invented new and useful Improvements in Writing Instruments, of which the following is a specification.

The invention relates to stationery, and 10 more particularly to writing instruments of the fountain pen type, and has for an object to provide a writing instrument for use in the manner of a lead pencil or a fountain pen.

15 The invention embodies, among other features, the provision of a unitary member including a fountain pen and a pencil member, the pencil member being normally arranged within the pen casing or member so 20 that the device can be used as a pencil or fountain pen.

In the further disclosure of the invention reference is to be had to the accompanying drawings, constituting a part of this specification, in which similar characters of reference denote corresponding parts in all the 25 views, and in which:

Figure 1 is a vertical longitudinal sectional view of my device, showing the pen 30 in position for writing; Fig. 2 is a similar view showing the pencil in position for writing; Fig. 3 is a fragmentary enlarged vertical longitudinal sectional view of the pencil member, showing the manner of advancing 35 or retreating the lead; Fig. 4 is a vertical transverse sectional view taken on the line 4—4 in Fig. 3; Fig. 5 is a perspective view of the lead actuating member; Fig. 6 is a fragmentary vertical transverse sectional view 40 taken on the line 6—6 in Fig. 1.

Referring more particularly to the views, I provide a casing 10 constituting a reservoir 45 11 adapted to hold ink or some other similar writing fluid and having a sleeve-like member 12 threaded on one end thereof, with the tubular portion of the member 12 extending within the casing 10, a suitable collar 13 being arranged on the member 12 and adapted to abut against one end of the casing 10 to limit the screwing up action of the member 50 relatively to the casing and also provided for a purpose that will be herein-after more fully disclosed.

A pen carrying rod 14 has threaded connection 55 with one end of a pencil member 15 and which includes a screw thread 16 in

threaded engagement with the interior of the member 12, the other end of the pen carrying rod 14 having a suitable nib 17 of the type usually employed in connection 60 with fountain pens, suitably attached thereon. Now it will be apparent that by rotating the pencil member 15, the same will be advanced or retreated relatively to the member 12 and thus the rod 14 and nib 17 65 will be advanced or retreated in the reservoir 11 formed by the casing 10.

A tubular actuating member 18 has one end thereof constituting an interior seat 19 adapted to be engaged by a perforated 70 hexagonal head 20 formed on the pencil member 15 and whereby the pencil member will be locked relatively to the actuating member 18 when the same is rotated, one end of the said actuating member being 75 adapted to encircle the projecting collar 13 of the sleeve-like member 12, and the said actuating member 18 furthermore being preferably made of the same material as the casing 10 so as to present a neat and effective 80 appearance. Now when the actuating member is rotated upon the casing 10 it will impart rotation to the pencil member 15, thus through the medium of the screw thread 16 within the member 12 advancing or retreating 85 the nib 17 relatively to the reservoir 11 so that the nib can be moved into or out of writing position as will be readily understood by referring to the views, it being further apparent that when the nib is in 90 writing position and is moved out of writing position the pencil member 15 will be advanced relatively to the casing 10 in order that the nib 17 can be moved entirely within the reservoir 11 formed by the casing 10. 95

A cap 21 is adapted for threaded engagement with an end of the casing 10 in order to close the reservoir 11 when the nib 17 lies therein and the actuating member 18 includes a reduced neck 22 also adapted to receive and support the cap 21 when it is desired to use the nib 17. It will thus be seen that the cap 21 performs two functions in that when it encircles one end of the casing 10 it closes the reservoir 11, whereas when 105 the cap is mounted on the neck 22 it incloses the pencil member 15 and permits of advancing the nib 17 from within the reservoir 11 to writing position.

An interiorly threaded collar 23 is secured 110 within the pencil member 15 and constitutes a part thereof and arranged to slide within

the collar is a longitudinally slotted member 24 adapted to receive one end of a lead 25 therein and grip the same, a lead operating member 26 being arranged to slide within the member 24 and including teeth 27 having threaded engagement with the inner surface of the collar 23 so that when a tip 28, swiveled at one end of the actuating member 18 and having rigid connection with the member 24 through the medium of a clamping band 29, is rotated upon the actuating member 18 the lead 25 will be advanced or retreated relatively to the collar 23 secured in the pencil member 15 and forming a part thereof.

From the foregoing description it will be apparent that the sleeve-like member 12 not only forms a closure for one end of the reservoir 11 but acts as a medium for insuring the proper operation of the pen carrying rod 14 or the pencil member 15 so that the device described can be used either as a fountain pen or pencil, the operation of the pencil or fountain pen portions of the device being accomplished through the medium of the pencil member and which connects the two portions, as mentioned heretofore, the said pencil member being actuated by the actuating member 18 swiveled on the casing 10.

In order to limit the retreating movement of the pen carrying rod 14, a plurality of diametrical pins 30 project from the rod and are adapted to abut against one end of the sleeve-like member 12, the movement of the

pen carrying rod in the opposite direction being limited by an end of the pencil member 15 abutting against an enlarged portion of the sleeve-like member 12.

Having thus described my invention, I claim:

In a writing instrument, a casing, a member threaded in one end of the casing, a pencil member movably threaded in the first mentioned member, a tubular actuating member encircling the casing and engaging the pencil member to turn the same when the actuating member is rotated on the casing, a collar on the first mentioned member and adapted to abut against the casing to hold the first mentioned member in said casing, said collar being encircled by said actuating member, a tip swiveled on one end of the actuating member, and a lead carrying member slidable in the pencil member and extending through and associated with said tip whereby, when said actuating member is rotated in one direction, said pencil member will be advanced in said first mentioned member and when said actuating member is rotated in the other direction said pencil member will be retreated in said first mentioned member.

In testimony whereof I affix my signature in presence of two witnesses.

HERMAN G. SCHROEDER.
